Primary Examiner — April Rivas(74) *Attorney, Agent, or Firm* — Donald S. Showalter; GrayRobinson, P.A.(57) **CLAIM**

The ornamental design of a case with an extendable handle, as shown and described.

DESCRIPTION

FIG. 1 is a front perspective view of our ornamental design of a case with an extendable handle with its handle in an extended position;

FIG. 2 is a bottom perspective view thereof;

FIG. 3 is a rear view thereof;

FIG. 4 is a front view thereof;

FIG. 5 is a right side view thereof;

FIG. 6 is a left side view thereof;

FIG. 7 is a top plan view thereof;

FIG. 8 is a bottom plan thereof;

FIG. 9 is a front perspective view of our ornamental design of the case with an extendable handle illustrated in FIG. 1 with its handle in a retracted position;

FIG. 10 is a bottom perspective view thereof;

FIG. 11 is a rear view thereof;

FIG. 12 is a front view thereof;

FIG. 13 is a right side view thereof;

FIG. 14 is a left side view thereof;

FIG. 15 is a top plan view thereof; and,

FIG. 16 is a bottom plan view thereof.
